UNITED STATES PATENT OFFICE.

CHARLOTTE J. TAYLOR, OF CARBON, INDIANA.

DESIGN FOR A STAND.

SPECIFICATION forming part of Design No. 37,343, dated February 14, 1905.

Application filed December 22, 1904. Serial No. 237,983. Term of patent 14 years.

To all whom it may concern:

Be it known that I, CHARLOTTE J. TAYLOR, a citizen of the United States, residing at Carbon, in the county of Clay and State of Indiana, 5 have invented a new, original, and ornamental Design for a Stand, of which the following is a specification, reference being had to the accompanying drawing, forming a part thereof.

The accompanying drawing discloses a perspective view of the design.

What I claim as new, and desire to secure by Letters Patent, is—

The ornamental design for a stand, as shown.

CHARLOTTE J. TAYLOR.
